TAIL STOCK FOR AUTOMATIC LATHES

Filed Jan. 22, 1927

Patented Nov. 6, 1928.

1,690,601

UNITED STATES PATENT OFFICE.

JOHN J. THACHER, OF WETHERSFIELD, CONNECTICUT, ASSIGNOR TO PRATT & WHITNEY COMPANY, OF NEW YORK, N. Y., A CORPORATION OF NEW JERSEY.

TAILSTOCK FOR AUTOMATIC LATHES.

Application filed January 22, 1927. Serial No. 162,779.

This invention relates to an improved form of tailstock adapted for use in an automatic lathe such as described and claimed in patent to Muller 1,252,928.

More particularly the invention relates to operating mechanism for a tailstock spindle such as shown and described in my previously granted Patent 1,545,074.

An object of the present invention is to provide adjusting means for a tailstock spindle adapting the tailstock to be positioned along the bed of the lathe for different lengths of work without requiring re-adjustments to be made of any parts for operating the tailstock.

Another object of the invention is to provide improved operating mechanism for a lathe spindle to frictionally force the tailstock spindle forwardly or rearwardly into and out of operative engagement with work in the lathe in any adjusted position of the tailstock.

Another object of the invention is to provide an oscillatory shaft within the base of the lathe adapted to be oscillated by cam means, the oscillatory shaft being connected through a spline to actuating means for the spindle.

With these and other objects in view, my invention consists in the features of construction and operation set forth in the following specification and illustrated in the accompanying drawing.

In the accompanying drawing annexed hereto and forming a part of this specification, I have shown my invention embodied in a tailstock for an automatic lathe, but it will be understood that the invention can be otherwise embodied and that the drawings are not to be construed as defining or limiting the scope of the invention, the claims appended to this specification being relied upon for that purpose.

In the drawing:

Figure 1 is a partial front elevation of an automatic lathe provided with the present form of tailstock and actuating means.

Fig. 2 is an end elevation of the same.

Fig. 3 is a sectional view taken upon the line 3—3 of Fig. 1.

Fig. 4 is a fragmentary plan view, partly in section, showing the operative connection between the pivotally mounted lever and the oscillatory shaft.

Fig. 5 is a detail portion of the invention, and

Fig. 6 is a detail view of a hand adjusting lever.

In the above mentioned drawing I have shown but one embodiment of the invention which is now deemed preferable, but it is to be understood that changes and modifications may be made within the scope of the appended claims without departing from the spirit of the invention.

Briefly and in its broadest aspect, my invention comprises the following principal parts: first, a tailstock comprising a frame adapted to be adjusted to any position along the ways of a lathe; second, a tailstock spindle slidably mounted for movement longitudinally within the tailstock; third, a collar frictionally engaging the spindle; fourth, a pivotally mounted lever engaging this collar so that oscillatory movement of the lever will move the collar and force it to frictionally move the spindle in either direction; fifth, a segmental gear formed on this pivotally mounted lever; sixth, a corresponding segmental gear splined to an oscillating shaft mounted within the lathe bed so that the oscillating lever may be actuated by oscillation of the shaft with the tailstock in any position; and seventh, a cam operated lever to oscillate the shaft.

Referring more in detail to the figures of the drawing, the tailstock 10 is shown as a frame mounted slidably upon suitable ways 11 extending longitudinally along the base 12 of a lathe, a portion of the base being shown in Figs. 1 and 2. By means of a nut 13 and screw 14 extending above the tailstock 10, the tailstock 10 may be secured rigidly to the base 12 in any adjusted position. As these securing means form no part of the present invention, it is not thought that further description is necessary. Also, as shown in Figs. 1 and 3, the tailstock 10 is divided horizontally, the upper portion indicated by 10 being laterally adjustable relative to the lower portion 15 by adjusting screws 16 of the usual type shown in Figs. 1, 3 and 4.

Extending longitudinally within the tailstock 10 is a slide member 17 having a work engaging center 18 at one end. Frictionally engaging this slide 17 is a collar member 19 which may be adjusted to contact with the slide 17 with any desired pressure by adjustment of the screw 20 shown most clearly in Fig. 3. This collar 19 is adapted to engage the slide 17 firmly enough to force

the slide 17 into contact with the work but, upon engagement of the center 18 with the work, the collar 19 may move forwardly over the slide 17 sufficiently far to engage a roller 21 with a clamping lever 22 similar to one shown and described in my above mentioned Patent 1,545,074.

In order to actuate this frictionally mounted collar 19, a shaft 24 is mounted for rotation within the base 12 and is suitably held against endwise movement. At one end of the lathe a bracket 25 is provided having a rotatably mounted sleeve 26 within which the shaft 24 is keyed. This sleeve 26 is attached 15 to a depending oscillating lever 27 adapted to be actuated by suitable cams 28 and 29 on the end of a main cam shaft 30 within the base 12. As shown in Fig. 2, the sleeve 26 and lever 27 are adapted to be angularly adjusted 20 within narrow limits by means of oppositely disposed adjusting screws 31. It will be seen from this construction that rotation of the main cam shaft 30, which is rotated in one direction during operation of the lathe, will 25 force the lever 27 to be oscillated, this oscillatory movement correspondingly oscillating the shaft 24 extending along the upper portion of the base 12.

Splined to this oscillating shaft 24 is a 30 member 32 carrying a segmental bevel gear 33 adapted to be engaged by a corresponding segmental bevel gear 34 on the lower end of the pivotally mounted lever 35. This lever 35, as shown in Figs. 2 and 4, is mounted 35 within the lower portion of the tailstock lower member 15 upon a short transverse shaft 36 so that as the oscillating shaft 27 oscillates back and forth by action of the cams 28 the pivotally mounted lever 35 will be correspondingly actuated.

At the upper end of this pivotally mounted lever 35 are gear teeth 37 adapted to engage rack teeth 38 formed on a horizontal surface of the collar 19 mounted on the spindle 17. 45 It will be seen, therefore, that oscillatory movements of the lever 27 due to the cams 28 and 29 on the main cam shaft 30 will cause the collar 19 to be positively moved back and forth relative to the tailstock 10 and this movement of the collar 19 will correspondingly frictionally move the spindle 17 into and out of work engaging position.

The cams 28 and 29 are so positioned that when a blank is to be mounted in the lathe 50 the oscillating lever 27 is moved toward the axis of the main cam shaft 30. This movement, through the oscillating shaft 27, the segmental gears 33 and 34 and the pivotal lever 35 moves the collar 19 and spindle 17 toward the work.

A transverse locking bolt 40 is provided in the tailstock adapted, upon being slightly tilted, to bind against the spindle 17. This 55 may be operated in the same manner as in my previously granted patent by the resilient

arm 22 engaging the roller 21 on the saddle 19. Also, as in my previously granted patent, the roller 21 is mounted on the lower end of a handle 43 pivotally mounted on the saddle 19. By oscillating the handle 43 this roller 21 may be moved into and out of operative position.

What I claim is:

1. A tailstock for lathes comprising in combination, a frame adapted to be adjustably positioned on a lathe bed, a spindle longitudinally movable therein, means to move said spindle within said frame comprising an oscillating shaft mounted adjacent the frame, a pivotally mounted lever adapted to be actuated by oscillatory movement of said shaft, and means frictionally connecting said pivotally mounted lever and spindle. 75

2. A tailstock for lathes comprising in combination, a frame adapted to be adjustably positioned on a lathe bed, a spindle longitudinally movable therein, means to move said spindle within said frame comprising an oscillating shaft mounted adjacent the frame, cam means to positively oscillate said shaft, a pivotally mounted lever adapted to be actuated by oscillatory movement of said shaft, and means connecting said pivotally mounted lever and spindle. 85

3. A tailstock for lathes comprising in combination, a frame adapted to be adjustably positioned on a lathe bed, a spindle longitudinally movable therein, means to move said spindle longitudinally comprising an oscillating shaft adjacent the frame and extending parallel to said spindle, a pivotally mounted lever cooperating with said oscillating shaft whereby said lever is adapted to be oscillated by oscillatory movement of said shaft, a collar frictionally engaging the spindle, and means connecting said pivotally mounted lever and said collar. 95

4. A tailstock for lathes comprising in combination, a frame adapted to be adjustably positioned on a lathe bed, a spindle longitudinally movable therein, means to move said spindle within said frame comprising an oscillating shaft adjacent the frame and extending parallel to said spindle, a pivotally mounted lever cooperating by means of segmental gears on said pivotally mounted lever and said oscillating shaft with said shaft whereby said lever is adapted to be oscillated by oscillatory movement of said shaft, and means frictionally connecting said pivotally mounted lever and spindle. 100

5. A tailstock for lathes comprising in combination, a frame adapted to be adjustably positioned on a lathe bed, a spindle longitudinally movable therein, a collar slidably mounted on said slide, means to move said spindle within said frame comprising an oscillating shaft mounted adjacent the frame, a pivotally mounted lever adapted to be actuated by oscillatory movement of said shaft, 115 120 125 130

and gear toothed means connecting said pivotally mounted lever and said collar.

6. A tailstock for lathes comprising in combination, a frame adapted to be adjustably positioned on a lathe bed, a spindle longitudinally movable therein, means to move said spindle within said frame comprising an oscillating shaft mounted adjacent the frame,

a cam operated oscillating lever connected to said shaft, a pivotally mounted lever adapted to be actuated by oscillatory movement of said shaft, and gear toothed means connecting said pivotally mounted lever and spindle. 10

In testimony whereof, I hereto affix my signature.

JOHN J. THACHER.
